UNITED STATES PATENT OFFICE

90,885

DESIGN FOR A KITCHEN CABINET

John L. Houck, Nappanee, Ind., assignor to Coppes Bros. & Zook, Inc., Nappanee, Ind., a corporation of Indiana

Application August 24, 1933. Serial No. 49,099

Term of patent 7 years

To all whom it may concern:

Be it known that I, JOHN L. HOUCK, a citizen of the United States, residing at Nappanee, in the county of Elkhart and State of Indiana, have invented a new, original, and ornamental Design for a Kitchen Cabinet, of which the following is a specification, reference being had to the accompanying drawing, forming a part thereof, in which:

Figure 1 is a view in perspective of the kitchen
cabinet showing the front closed; and Figure 2 is a similar view showing the front open and the work table extended.

I claim:

The ornamental design for a kitchen cabinet,
as shown and described.

JOHN L. HOUCK.
